[57] CLAIM

The ornamental design for a draw-down strap, as shown and described.

DESCRIPTION

FIG. 1 is a perspective view of the draw-down strap showing my design in a closed or locked position.

FIG. 2 is a side elevational view of the draw-down strap of FIG. 1, the opposite side elevational view being the mirror image.

FIG. 3 is a top plan view of the draw-down strap of FIG. 1.

FIG. 4 is a front elevational view of the draw-down strap of FIG. 1.

FIG. 5 is a bottom plan view of the draw-down strap of FIG. 1; and,

FIG. 6 is a rear elevational view of the draw-down strap of FIG. 1.
